DRILL BIT HOLDER

Leonard Travis, Sidney, Iowa

Application July 21, 1938, Serial No. 220,536

3 Claims. (Cl. 51—219)

This invention relates to a drill bit holder and has for an object to provide a drill bit holder which is adjustable for different sizes of drill bits, such as small, medium and large size drill bits, and is so designed that the particular drill bit may be held against a grinding wheel at the proper angle according to the size of the drill bit in accordance with the particular work the drill bit is to be used.

10 Still a further object of this invention is to provide a drill bit holder which may be made in several different forms as desired all of which forms, however, are so designed that they may be mounted on the same stand.

15 A still further object of this invention is to provide a stand for the drill bit holder which stand includes both horizontal and vertical ways permitting horizontal and vertical adjustment relative to the position of the grinding wheel, 20 which stand is further provided with a graduated feed means so that both sides of the drill bit may be ground exactly alike.

With the foregoing and other objects in view, as will hereinafter become apparent, this invention comprises the combinations, constructions and arrangements of parts hereinafter set forth, disclosed, claimed and illustrated on the accompanying drawings.

In these drawings:

30 Fig. 1 is a front elevational view of one form of drill bit holder which is adjustably mounted on the bit arm pin.

Fig. 2 is a section view on line 2—2 of Fig. 1.

Fig. 3 is a section view on line 3—3 of Fig. 1.

35 Fig. 4 is a fragmentary view of the drill bit holder and stand partly in section.

Fig. 5 is a plan view of a form of holder differing from Fig. 1 in that it is not adjustable.

Fig. 6 is a sectional view on line 6—6 of Fig. 5.

40 Fig. 7 is an end view on the lip end of Fig. 5.

Fig. 8 is an end view on the lip end of another form of holder, having an adjustable lip.

Fig. 9 is a plan view on line 9—9 of Fig. 8.

Fig. 10 is a perspective view of still another form of this invention, having an adjustable drill holding trough, partly in section, and mounted in operative position on the stand used for all forms of this invention.

Fig. 11 is a top plan fragmentary view of Fig. 10.

50 Fig. 12 is a sectional view on line 12—12 of Fig. 11.

Fig. 13 is a plan view on line 13—13 of Fig. 12.

There is shown at 10 in Fig. 1 one form of the drill bit holder which may be mounted on the stand 11 for operation for grinding a drill bit 12

against a grinding wheel 13, the grinding wheel 13 being rotated by any convenient form of power electrical, manual or otherwise.

The holder 10 includes a drill bit trough 14 adjustably mounted on a pin 15 which is slidably 5 inserted in the bearing 12 of the stand 11.

The trough 14 has an adjustable stop 16, fixable in position by means of a thumbscrew 17, against which stop 16 the end of the drill 12 may abut.

The cutting end 18 of the drill 12 rests against 10 a lip 19 on the end of the trough 14 and may be held firmly thereagainst by means of a clamp arm 20. This clamp arm 20 is pivoted on a pin 21 extending through a pair of spaced abutments 22 which extend from the side of the trough 14. 15

Another pin 23 extending between the same abutments 22 pivotally supports a bolt 24 which extends through a suitably placed slot in the clamp arm 20, and holds the clamp arm 20 by means of the wing nut 25, in clamping position 20 over the drill bit 12.

This drill holder 10 is adjustably mounted on the pin 15 by means of a pair of spaced depending flanges 26 and 27, between which is fitted a flattened head 28 forming an integral angular extension of the pin 15, the head 28 being shaped substantially as shown with the long slot 29 and the three crosscuts 30, 31 and 32.

The slot 29 cooperates with a thumbscrew 33 for holding the head 28 pivotally and slidably 30 between the flanges 26 and 27. A second thumbscrew 34 extending through flange 27 and threaded into the flange 26 is provided with a thinned shank 35 which will freely fit in any one of the crosscuts 30, 31 and 32, permitting the trough 35 14 to be slidably adjusted on the shank of the screw 33 within the slot 29 of the head 28 and bring the thumbscrew 34 into registry with the selected position in any one of the crosscuts 30, 31 and 32, according to the degree that the drill 40 cutting end 18 is to be ground.

In operation it is found desirable to place these crosscuts so that the selected angles may have 30, 59 and 65 or 70 degree positions indicated thereon, crosscut 30 being for small drills, crosscut 31 for medium drills, and crosscut 32 for large drills. As shown in Fig. 4, the drill holder is set at the 59 degree position for a small drill, with the thumbscrew shank 35 at the full line position. If shank 35 be placed fully into the cross cut at the dotted position 30°, the small drill would be sharpened at a 30 degree angle. Similarly, it may be placed near the edge of the crosscut at the 70° position to sharpen it at a 70 degree angle. Instead of 70 degrees, this 55

angle may be selected by some manufacturers as 65 degrees. In the same way, medium or large drills may be adjusted in their crosscuts 31 and 32.

- 5 In grinding the drill 12 the drill holder 19 is placed with the pin 15 in the bearing 72 of the stand 11. This bearing 72 is formed on the end of a spring leaf 26 and secured by screws 37 to enlarged foot 38 of an upright 39.
 10 This upright 39 ends in a pointer 40 cooperating with graduations 41 on a feed wheel 42 which is threaded on a bolt 43 carrying a coiled compression spring 44 between the leaf spring 36 and the back of the upright 39.
 15 The upright 39 is secured by means of a wing nut and bolt 46 and slot 47 to a leg 45 of the angle bracket 48. This angle bracket 48 is similarly adjustably secured on horizontal ways 49 of a base 50 by means of a wing bolt and nut 51 and slot 52. The base 50 is secured as by stud bolts 53 to the same foundation 54 on which the grinding wheel 13 is supported.

In operation the drill bit 12 is secured by the clamp arm 29 in the drill trough 14, with its cutting end 18 resting against the lip 19, the angle of the pin 15 to the trough 14 having been selected by adjusting its head in the particular crosscut desired. The stand 11 is then adjusted vertically and horizontally as desired to bring 25 the bit cutting end 18 into contact with the grinding wheel 13 either at the center of the grinding wheel or above or below as desired, its being observed at the center is usually the preferable position. Then with the grinding wheel 30 13 in rotation the drill cutting end 18 may be moved across the grinding part of the wheel 13 by sliding the pin 15 in or out of the bearing 72 at the same time it may be moved up and down about the pin 15 and bearing 72 as a center. As 35 the grinding proceeds the feed wheel 42 is rotated to keep the bit cutting end 18 in contact with the grinding surface of the wheel 13 as it is being sharpened.

After one side is sharpened the drill bit 12 is rotated 180 degrees within the holder to bring 40 its other face against the grinding wheel after first observing the position the particular graduation 41 relative to the point of 40. The feed wheel is then backed away permitting the drill 45 to be put in position again. Then the feed wheel 42 is gradually rotated again the exact same amount as determined by the position 41 thus grinding both faces of the cutting end identically.

In the form of the invention shown in Figs. 5, 6 and 7 those parts which are the same as 50 in the first form of Figs. 1-4 bear the same reference figures. Instead of pin 15 of this form being adjustable relative to trough 14 it is fixed in an abutment 55 extending from the trough 14 near the end or opposite the spaced abutments 22, otherwise the construction and 55 operation of this form of the invention is identical with that just described.

The form of the invention shown in Figs. 8 60 and 9 is identical with that shown in Figs. 6 and 7, except that it has an adjustable lip 59 adjustably secured thereto by a bolt and wing nut 60 extending through slot 61 in the side of the trough.

70 Identification marks 60 alongside the slot show the proper positioning for the bolt and wing nut 60 to thus position the lip 59 for large, medium and small sized drill.

In the form of drill bit holder shown in Fig. 75 12 and Fig. 13, and likewise shown in a similar

position with the stand in Fig. 10 and Fig. 11, the pin 15 forms integral angular extension of a drill bit arm 63. This drill bit arm 63 carries a drill bit trough 64 identical with the end of the drill bit trough of each of the other inventions, 5 having the same drill bit clamp arm 29 and spaced abutments 22. This trough 64 is adjustably mounted along the end of the drill bit arm 63 adjacent pin 15 by means of a thumbscrew 65 extending through the trough bearing 66 into a 10 selected depression 67, 68 or 69 according to whether the drill bit is small, medium or large size. A back stop 70 is adjusted on the arm 63 by means of a thumbscrew 17 to hold it in proper position for the end of the drill bit 12 to abut 15 thereagainst.

The operation and construction of each of the forms should be apparent from the above description in the first form of the invention.

While the device has been shown and the 20 structure has been described in detail, it is obvious that this invention is not to be considered limited to the exact form disclosed and that changes may be made therein within the scope of what is claimed without departing from the 25 spirit of the invention.

Having thus set forth and disclosed the nature of this invention, what is claimed is:

1. A device for holding a drill bit in the proper drilling angle while being ground, said device 30 comprising a stand and a drill receiving and securing member journaled on said stand, said stand including a bearing member, said drill receiving and securing member including a pin journaled in said bearing member and a drill 35 carrying arm, said arm including an adjustable stop member against which one end of the drill may abut and a clamp member for securing the drill on said arm with its drill end projecting therebeyond, said arm including a trough and 40 a lip on the end thereof against which lip the drill may rest, and means for adjusting the relation of the drill carrying arm to its bearing pin, said relation adjusting means comprising an adjustable mounting between said bearing pin and 45 said trough, said adjustable mounting comprising an abutment depending from said trough and means for adjustably securing said abutment to said bearing pin, said means including an angular extension of said bearing pin extending through 50 said abutment and thumbscrew means for securing said abutment at different graduated positions along said bearing pin extension, said extension including a plurality of depressions therein, said thumbscrew cooperating with a selected 55 depression in any one of said depressions to fix the angular relation of said trough to said pin.

2. In a device for holding a drill bit in a selected drilling angle while being ground, a stand and a drill receiving and securing member journaled on said stand, said stand comprising a base, an angular bracket having a horizontal leg and a vertical leg, means for slidably securing said horizontal leg on said base, journaling means, means for adjustably securing said journaling means 65 on said vertical leg, said journaling means including a leaf spring fastened at one end to said adjustable securing means, a journal bearing at the other end of said leaf spring and graduated means for drawing said journal bearing end to 70 wards the plane of the vertical leg.

3. In a device for holding a drill bit in a selected drilling angle while being ground, a stand and a drill receiving and securing member journaled on said stand, said stand comprising a base, an 75

angular bracket having a horizontal leg and a vertical leg, means for slidably securing said horizontal leg on said base, journaling means, means for adjustably securing said journaling means on said vertical leg, said journaling means including a leaf spring fastened at one end to said adjustable securing means, a journal bearing at the other end of said leaf spring, said adjustable securing means comprising an upright 5
10 slidably secured to said vertical leg, said upright

having an abutment on its base, said leaf spring being mounted at one end to said upright abutment and graduated means at the other end of said leaf spring for drawing said bearing end toward said upright, said graduated means including a pointer on said upright, a bolt passing through said bearing end of said leaf spring and said upright, and a graduated wheel threaded on said bolt cooperating with said pointer. 5

LEONARD TRAVIS. 10
